UNITED STATES PATENT OFFICE.

GEORGE F. STILLMAN, OF SYRACUSE, NEW YORK; MABEL D. STILLMAN, ADMINISTRATRIX OF SAID GEORGE F. STILLMAN, DECEASED, ASSIGNOR TO THE SMITH PREMIER TYPEWRITER COMPANY, OF SYRACUSE, NEW YORK, A CORPORATION OF NEW YORK.

TYPE-WRITING MACHINE.

No. 893,397.

Specification of Letters Patent. Patented July 14, 1908.

Application filed April 21, 1904, Serial No. 204,244. Renewed January 19, 1907. Serial No. 353,139.

To all whom it may concern:

Be it known that I, GEORGE F. STILLMAN, of Syracuse, in the county of Onondaga, in the State of New York, have invented new 5 and useful Improvements in Type-Writing Machines, of which the following, taken in connection with the accompanying drawings, is a full, clear, and exact description.

This invention relates to improvements in 10 typewriting machines and refers more particularly to the type bar and its hanger to be used in connection with visible writing machines.

In visible writing machines the full complement of type bars are ordinarily confined 15 within a segment of less than a half circle. This requires that the individual hangers be placed side by side and close together in a substantially circular arc having its center 20 at or near the printing point.

One of the objects of my invention is to make the individual hangers and the joint between each type bar and its hanger, as narrow as possible and at the same time give 25 each type bar a comparatively broad bearing concentric with its axis of revolution.

Another object of my invention is to provide each type bar with opposite anti-friction, bearing points which are disposed 30 concentrically around the axis of revolution of the bar equidistant from each other so as to oppose the end thrust and axial movement of the bar, and thus maintain the perfect alinement of the type at the printing point.

To the above and other ends which will 35 hereinafter appear, my invention consists of the features of construction, arrangements of parts and combinations of devices set forth in the following specification and particularly pointed out in the appended claims.

In the drawings, Figure 1 is a side elevation of my improved type bar and hanger construction, the hanger being shown secured to a segment and the type bar broken away, 45 the type bar being shown in normal position in full lines and in printing position in dotted lines. Fig. 2 is an enlarged sectional view of the same taken on the line 2—2 of Fig. 1. Figs. 3 and 4 are opposite face 50 views of one of the individual hangers. Fig. 5 is a sectional view similar to Fig. 2 of a modified form of type bar and hanger in which the anti-friction balls and pockets are

formed in the heel of the type bar instead of in the hanger. 55

Similar reference characters indicate corresponding parts in all the views.

I have shown my invention in the present instance as it would be applied in a front strike machine, though it should be understood that the type bar and hanger construction of my invention may be employed in various styles of typewriting machines.

In carrying out the objects stated, I provide a support —1— which usually consists 65 of a segment of a metal ring and is fixedly mounted in the frame of the machine in any desired manner (not necessary to herein illustrate or describe) for the purpose of supporting a number of individual type bar 70 hangers —2—. These hangers —2— are preferably secured in an upright position side by side upon the segment —1— by suitable fastening means, as screws —3—, and each is provided with a transverse circular 75 opening —4—, Figs. 2, 3 and 4, having opposed annular walls —5— which are beveled transversely at an angle with the axis of the opening to form a V-shaped annular rib —6— surrounding the opening. The bevelled sides of this rib are each formed with a series of (in this instance three) ball pockets or sockets —7— having ball seats —8— at their bases to receive and encompass suitable balls —9—. These sockets are disposed at substantially right angles to their 85 respective sides and those of one side are arranged in close proximity to, but slightly in advance, circumferentially, of those of the opposite side so as to stagger the opposed 90 pockets with each other, as will be understood by a comparison of Figs. 3 and 4, and thus permit the use of comparatively thin stock for the hangers.

The bases of the sockets are preferably 95 counterbored at —10— to reduce the area of the ball seats, thus forming a narrow annular rib or seat for each ball, and these sockets are of such depth that when the balls are seated they protrude slightly 100 through the open sides of their respective sockets to form bearing points for the type bars —11—.

The heel of each type bar is bifurcated to receive its hanger and to form opposed arms 105 or bearing plates —12— at opposite sides

of the hanger for engaging the protruding parts of the balls —9—. These bearing plates are preferably formed of separate pieces of thin, hard steel secured to the 5 opposite sides of the type bar proper by rivets —13— to cover the opposite ends of the opening —4— and are provided with frusto-conical bearing faces —14— which ride upon their respective ball bearings —9— 10 in the opposite sides of the V-shaped annular rib —6—. As best seen in Fig. 2 the centers of these plates are depressed or dished in opposite directions and pass in opposite directions into the opening —4— for the 15 purpose of forming the conical or V-shaped bearings —14— and are clamped together at the axis of the type bar by suitable fastening means as an eyelet —15—.

The construction seen in Fig. 5 is substantially a reversal of that seen in Fig. 2; that is, the type bar as —11'— is formed with a circular opening —4'— and a V-shaped annular rib having opposed beveled annular bearing faces —5'— in which are formed 20 the sockets or ball pockets —7'— similar to the pockets —7— in the hanger in Fig. 2. In this construction the hanger is provided with opposed bearing plates having frusto-conical bearings —14'— upon which ride 25 suitable balls —9'— in the sockets —7'— and these plates are clamped together at the center of the opening by a screw —15'— or other suitable means.

It will be seen that in both of the constructions described, the rivet or eyelet —15— and the screw —15'— constitute means at the axis of the type bar for effecting an adjustment of the side plates of the type bar or hanger in planes parallel to the median plane of the 40 type bar, in order to effect an adjustment of the bearings or to compensate for wear if there be any. It will also be seen that the side plates 12 in Fig. 2 and the corresponding plates in Fig. 5 overlap and entirely inclose 45 the eyes or openings —4— and —4'— respectively and the bearings, and that both constructions provide a dust proof bearing to exclude the admission of dust to the bearing of the type bar in any direction. This 50 feature is of considerable importance in front strike typewriting machines. In such constructions the type bar bearings are beneath and in substantially vertical alinement with the front face of the platen, and dust, grit 55 or rubbings from the paper at the front face of the platen fall upon or get into the bearings of the type bars unless means be provided to exclude the same.

The constructions described provide for 60 locating two series of balls in suitable pockets around the center of oscillation of the type bar so as to form bearing points which are opposed both circumferentially and axially, and to draw the bearing plates against the 65 balls from a central point, thereby estab-

lishing a uniform pressure on all bearing points and reducing the friction and lost motion to a minimum. This gives a comparatively broad concentric bearing for the bar some distance from its axis, thereby preventing a lateral movement of the type bar as it swings to the printing position and permits the use of a large number of type bars and hangers within a comparatively small space.

Having thus described my invention what I desire to secure by Letters Patent is:—

1. In a typewriting machine, a type bar and hanger therefor, one of the parts having opposed ball pockets and the other part having opposite arms covering adjacent pockets and balls seated in the pockets, and upon which the arms of said other part is mounted.

2. In a typewriting machine, a type bar and hanger therefor, one of the parts having a circular opening and opposed ball pockets in the walls of the opening and the other part having opposite annular bearings projecting into the ends of the opening, the balls in the pockets engaging the bearings of said other part.

3. In a typewriting machine, a type bar and hanger therefor, each of the parts having annular faces beveled transversely, the faces of one of the parts having a series of ball pockets and balls in the pockets engaging the adjacent annular face of the other part.

4. In a typewriting machine, a type bar and a hanger therefor, each part having opposed annular faces, the annular faces of one part each having a series of ball-pockets staggered with those of the other series, and balls in the pockets engaging the adjacent annular faces of and supporting the other part.

5. In a typewriting machine, a type bar and a hanger therefor, one of the parts having an annular rib V shape in cross section, each of the opposite faces of the rib being provided with a series of pockets spaced equidistant from each other and the other part having beveled annular bearings at the opposite sides of said rib, and balls in the pockets engaging the beveled bearings of the other part.

6. In a typewriting machine, a type bar and a hanger therefor, one of the parts having a circular opening and opposed pockets in the walls of the opening, and the other part having opposed bearings at opposite ends of the opening and covering said pockets, and balls in the pockets and engaging said bearings.

7. In a typewriting machine, a type bar and a hanger therefor, one of the parts having opposed circular rows of pockets in different planes about a common axis, and the other part having opposed annular bearings facing said pockets, and balls in the pockets engaging said faces.

8. In a type-writing machine, a type-bar

and a hanger therefor, one of the parts having opposite faces, each formed with a series of pockets and each pocket formed with a circular ball seat, the other part having opposite arms each formed with an annular bearing facing one series of pockets, and a ball seated in each pocket on its circular seat and engaging the adjacent annular bearing.

9. In a typewriting machine, a type-bar and a hanger therefor, one of the parts having a circular opening with transversely beveled annular walls, and the other part having opposite arms formed with transversely beveled annular faces projecting into the opposite ends of said opening, the beveled faces of one of the parts having separate individual ball-pockets, and balls between the walls of the opening and said annular faces and seated in said pockets.

10. In a typewriting machine, the combination of a type bar, a hanger therefor, one of the parts having ball containing pockets therein, and two sets of separated balls contained in said pockets, the centers of one set of balls being disposed to one side of the median plane of the type bar bearing and the centers of the other set of balls being on the opposite side of the median plane of said bearing.

11. In a typewriting machine, the combi-

nation of a type bar, a hanger, one of the parts having ball-encompassing pockets, each pocket having a circular ball seat, and balls contained in said pockets.

12. In a typewriting machine, the combination of a type bar, a hanger, one of the parts having ball-encompassing pockets, each pocket having a circular ball seat, and a bearing concentric with the axis of revolution of the type bar on the other part and with which all of said balls coöperate.

13. In a typewriting machine, the combination of a type bar, and a hanger, one of the parts having ball receiving pockets with the open mouths thereof disposed in opposite directions and each containing an anti-friction ball against which the other part bears.

14. In a typewriting machine, the combination of a type bar, and a hanger, one of the parts having ball containing pockets formed in the surface thereof, each pocket surrounding the ball contained therein on all except one side thereof where it bears on the other part.

In witness whereof I have hereunto set my hand this 18th day of April 1904.

GEO. F. STILLMAN.
